UNITED STATES PATENT OFFICE.

JOHN P. SIMMONS, OF SAN FRANCISCO, CALIFORNIA.

HYDRAULIC GIANT.

SPECIFICATION forming part of Letters Patent No. 642,853, dated February 6, 1900.

Application filed November 21, 1898. Serial No. 697,080. (No model.)

To all whom it may concern:

Be it known that I, JOHN P. SIMMONS, a citizen of the United States, residing at San Francisco, in the county of San Francisco and State 5 of California, have invented certain new and useful Improvements in Hydraulic Giants; and I do hereby declare the following to be a full, clear, and exact description of the same.

My invention relates to improvements in 10 hydraulic giants.

It consists in an improvement in the flexible joint, and is particularly applicable to the form of giant described and illustrated in my Patent No. 583,806, dated July 20, 1897. It also 15 consists in the other details of construction which will be fully described hereinafter, and pointed out in the claims.

The object of my invention is to provide a cheap, simple, and efficient hydraulic giant 20 so constructed that the lines of strain induced by the outrushing stream shall be brought low down toward its foundation, and, further, to so provide in its construction that the outflowing stream shall not be cramped or impeded by the vertical movement of the movable section or nozzle. I accomplish these 25 objects by means of devices illustrated in the accompanying drawings, in which—

Figure 1 is a side elevation of my device, 30 portions being in section to more clearly illustrate it. Fig. 2 is a detail of the ball-bearing joint.

A represents the stationary portion of a hydraulic giant, preferably made in the form of 35 an upturned elbow, in the lower portion of which the supply-pipe terminates. The upper portion of this pipe or elbow is provided with a spherical segment or socket. Surrounding this socket is an exterior flange or 40 lip a, in the under side of which is located a circular track, groove, or way a', adapted to receive and contain antifriction-balls. Surrounding the socket portion of the pipe A is a ring B, preferably formed with a flange or 45 lip b, projecting inwardly beneath the flange or lip a. In the ring B is provided a track, groove, or way b', corresponding with and opposing the track a', so arranged as to be adapted to receive between them antifriction-balls. 50 The lower face of the flange a and the upper face of the flange b are slightly separated and are preferably formed at an angle to the hori-

zontal plane, substantially as shown in the detail Fig. 2, in which the opposing faces are approximately at forty-five degrees to the horizontal plane. For convenience of construction the ring B is usually made in two parts, which parts are joined in any suitable way, preferably by a bolt, as shown at b². In the ring B is provided a bearing, (shown dotted in Fig. 1 at b³), one of such bearings in each of the two parts which form the ring B.

The movable section C of the giant is of curved and tapering form, as shown in Fig. 1. At its lower portion it is provided with a 65 spherical segment c, adapted to loosely fit the spherical socket of the lower stationary pipe A and form a ball-and-socket joint therewith. Each side of the curved movable section C is provided with a pin c', suitably secured there- 70 to and adapted to enter and engage with the bearings b³, thus forming a pivotal support for the movable section C upon the ring B. The lower opening of the spherical segment c is preferably frog mouthed or scarfed, as 75 shown in Fig. 1.

To prevent leakage in the ball-and-socket joint, a suitable packing, consisting of a flexible packing-ring D and a metallic holding-ring d', is provided. Antifriction-balls E are 80 provided in the tracks or ways a' and b'. By the construction here shown depressing the outer end of the curved movable section does not contract the available waterway, as in 85 giants heretofore constructed, and reversing the position of the ball and socket from the way heretofore constructed carries the point of suspension much closer to the foundation than it has been possible heretofore. The angular form of the faces of the flanges a and 90 b perform the desirable function of holding the ring B in place by providing metal in the flanges a' and b' to overhang the horizontal diameter of the antifriction-balls below and above, respectively.

The operation of the device is, speaking generally, the same as that of a hydraulic giant of ordinary form, except in regard to the effect of the construction particularly referred to herein. It is obvious that by having the male portion of the ball-and-socket joint a part of the movable section the section of the stream in the movable section does not vary by the vertical movement of its outer 95 100

end, as in the form of construction heretofore employed. Any diminution of the section which might take place in the stationary elbow by reason of the vertical swing of the movable section is provided for by the frog-mouth or scarfed shape of the water-inlet to the ball of the joint, a shape which is impossible in the ordinary form of construction. The angular character of the adjacent flange-faces simplifies the construction by obviating any special device to keep the ring B in working position.

Having now described my invention, what I claim as new, and desire to secure by Letters Patent, is—

1. A hydraulic giant comprising a stationary pipe having a socket, a curved movable

section provided with a ball-joint adapted to engage with said socket to form a ball-and-socket joint therewith and an exterior ring or washer adapted to oppose the water-thrust. 20.

2. A hydraulic giant comprising a stationary pipe having a socket, a curved movable section provided with a ball-joint adapted to engage with said socket to form a ball-and-socket joint therewith, a suitable water-tight packing between said ball and socket and a ring or washer adapted to oppose the water-thrust. 25

JOHN P. SIMMONS.
